UNITED STATES PATENT OFFICE.

JARVIS E. DAVIS, OF UNION, OREGON.

FIRE-ESCAPE.

SPECIFICATION forming part of Letters Patent No. 271,429, dated January 30, 1883.

Application filed May 27, 1882. (No model.)

To all whom it may concern:

Be it known that I, JARVIS E. DAVIS, of Union, in the county of Union and State of Oregon, have invented a new and useful Improvement in Fire-Escapes, of which the following is a full, clear, and exact description.

Reference is to be had to the accompanying drawings, forming part of this specification, in which similar letters of reference indicate corresponding parts in all the figures.

Figure 1 is a side elevation of my improvement. Fig. 2 is an end elevation of the same. Fig. 3 is a sectional plan view of a part of the same. Fig. 4 is a sectional elevation of a part of the same.

The object of this invention is to facilitate the escape of people from burning buildings when the ordinary egress-passages become impassible.

The invention consists in a fire-escape constructed with a truck having attached to it a base-frame provided with upright rods connected at their upper ends in pairs by cross-bars. Upon the upright rods slide bearings attached to the corners of a canvas-covered frame, which is held up by springs connected with the said base and top frames, and with interposed sliding side bars. The top frame is held from rebounding by ratchet-bars and spring-pressed pawls, which can be withdrawn to allow the top frame to be raised by the supporting-springs by arms attached to upright rack-bars, connected by levers and a rod, whereby both pawls can be withdrawn at the same time, as will be hereinafter fully described.

A represents an ordinary truck, upon which the apparatus is mounted, and which is provided with a tongue, B, or a tongue and drag-rope, for drawing the apparatus from place to place.

To the truck A is attached the base-frame C, springs being interposed, if desired. The frame C can be made of any desired length and breadth, and to its four corners are attached the lower ends of four rods, D. The end rods, D, are connected at their upper ends by cross-bars E.

Upon the upper parts of the four rods D are placed four bearings, F, which are attached to the corners of a frame, G, and which are made long to prevent them from binding upon the rods D as the frame G moves up and down.

Between the side bars of the frames C and

G are interposed three (more or less) bars, H, which have bearings formed in or attached to their ends to receive and slide upon the rods D. 55 The side bars, H, are separated from each other and from the side bars of the frames C G by spiral or other shaped springs, I, as shown in Figs. 1 and 2. The frame G is covered with canvas, J, or other suitable material, and may 60 also have a mattress or cushion, K, secured to it.

To the cross-bars H, next below the frame G, is attached a netting, L, of rawhide, or other suitable material, so as to re-enforce the canvas 65 J and prevent it from being torn or burst by a weight applied to it. With this construction, when the apparatus has been drawn to the side of a burning building from which all the people did not succeed in getting out before the 70 egress-passages became impassible, the people desiring to escape jump successively upon the covering of the frame G. As each person alights upon the covering of the frame G and forces the said frame downward, the several sets of 75 springs are put under tension successively, so that the downward movement of the frame will be stopped before the said frame encounters a rigid resistance, and the person will be saved from a shock. 80

The person using the escape is kept from being thrown off and injured by the rebound of the springs I by the ratchet-bars M and pawls N, which detain the frame G at its lowest point of descent. The ends of the ratchet-bars M are 85 attached to the bars E and to the end bars of the frame C, or to metal blocks O, attached to the said bars. The bars M are made square, and the ratchet-teeth are formed upon their inner sides. The pawls N slide in openings in 90 the inner sides of the metal blocks P, attached to the end bars of the frame G, and are held against the ratchet-bars M by springs Q, attached to the inner sides of the said end bars of the frame G, and which rest against the inner ends of the said pawls N. 95

In a slot or notch in each of the pawls N rests an arm, R, the outer end of which rests in a slot in the metal block P, and has a square hole formed through it to receive and slide 100 upon the square bar S. The bar S has round tenons formed upon its ends, which work in sockets in the metal blocks O.

To the bars S are rigidly attached arms or le-

vers T, which are connected by a rod, U, so that the two bars S will always turn together. With this construction the pawls N can be withdrawn to allow the frame G to be raised by the 5 springs I, ready to be again used by turning the bars S by means of either of the levers T.

Handles V can be attached to the rear end of the frame C for convenience in guiding and adjusting the apparatus.

10 Having thus fully described my invention, what I claim as new, and desire to secure by Letters Patent, is—

15 1. A fire-escape constructed substantially as herein shown and described, and consisting of the truck A, the base-frame C, the rods D, the top cross-bars, E, the top frame, G, having flexible cover J, the sliding side bars, H, the netting L, the springs I, the ratchet-bars and pawls M N, the springs Q, arms R, and bars 20 S, and the levers T and connecting-rod U, as set forth.

25 2. In a fire-escape, the combination, with the truck A, the base-frame C, upright rods D, and cross-bars E, of the frame G, having flexible cover J and sliding bearings F, the sliding side bars, H, and the interposed springs I, substantially as herein shown and described,

whereby a person can jump upon the covered top frame from a height without being injured, as set forth.

3. In a fire-escape, the combination, with the base-frame C and the sliding top frame, G, of the rack-bars M, the pawls N, and the springs Q, substantially as herein shown and described, whereby the top frame, when forced down by 35 the weight of a person jumping upon it, will be held from rebounding, as set forth.

4. In a fire-escape, the combination, with the spring-pressed pawls N and the ratchet-bars M, of the arms R, the bars S, the levers T, and 40 the connecting-rod U, substantially as herein shown and described, whereby the pawls can be readily withdrawn to allow the top frame to be forced up by the springs, as set forth.

5. The combination, with the frame G, of 45 the cross-bars H, the springs I, the canvas J, and the netting L, whereby those obliged to jump from a burning house may be received on something which will yield to the shock or striking force, as described.

JARVIS E. DAVIS.
